UNITED STATES PATENT OFFICE.

JOSEPH STOLPER, OF NEW YORK, N. Y., ASSIGNOR OF ONE-HALF TO LOUIS RABINOWITZ,
OF NEW YORK, N. Y.

SAFETY-RAZOR.

No. 927,188.

Specification of Letters Patent.

Patented July 6, 1909.

Application filed October 2, 1908. Serial No. 455,835.

To all whom it may concern:

Be it known that I, JOSEPH STOLPER, a citizen of the United States, and a resident of the city, county, and State of New York, have invented certain new and useful Improvements in Safety-Razors, of which the following is a specification.

My invention relates to improvements in safety razors and the object thereof is to provide an economical and simple razor of the safety type in which the blade may be readily removed and the razor cleaned. By arranging a front and back support for the blade which are hinged to open longitudinally the blade may be properly held for use with a double protection and the blade may be readily removed for cleaning. Furthermore in my improved razor, the arrangement is such that it may be handled in use similar to the old style or plain razor and the whole device, except the blade, is a unit and need only be opened on its hinge without separating its parts. The blades are removable and may be renewed from time to time. The details of construction of one embodiment of my invention will appear more fully hereinafter.

In the drawings forming a part of this application, Figure 1 is a plan view of my improved razor, partly broken away, Fig. 2 is a similar view showing the frame open, Fig. 3 is a cross section taken on the line 3—3 of Fig. 1, and Fig. 4 is a plan view of a blade.

The holder is formed of two members 1 and 2, which are hinged by a hinge 3 at one end so that both sections may be opened for the reception of a blade; and the two sections 1 and 2 form front and rear guards for the blade to protect the user and to form a substantial backing for the blade, which is preferably made of very thin metal. One of the members, preferably 1, is provided with means for holding such as the handle 4 which is preferably formed integral therewith and continuous therewith, though the handle may be varied. I have provided the member 1 with serrated guard teeth 5 and 6 along its edges which serve to protect the edges of

the blade 7, on the side away from the face of the user and these serrations, when the blade is in place, extend slightly beyond the cutting edges of the latter. The other member 2, of the frame preferably has straight edges 18 which do not extend quite as far out as the ends of the serrations 5 and 6, thus leaving a portion of the cutting edges of the blade exposed.

The hinge 3 I have provided with a spring 8, which surrounds the pin of the hinge and has one end 9 pressing against the frame member 2 and the other against the frame member 1 to force them apart. There is a catch for holding the frame closed, which I have formed of a sliding pin 11, in a recess in the handle, which is forced forward by a spring 12 to cause it to enter a recess 13 in the member 2, to lock the frame members closed. The catch may be released by pulling back the knob 14 which is secured to the pin 11.

I provide pins or posts 15, which are preferably carried by the member 1, which pass through the apertures 16 of the blade 7, for the purpose of determining the position of the blade in the holder and preventing any dislocation during use. By providing recesses 17 in the member 2 for the reception of the pins or posts 15, the frame members are held against any lateral disarrangement, should there be any play in the hinge. I prefer to form the frame members concavo-convex as shown, so that the blade will be gripped near the edges and so the surface of the frame coming against the face will be curved.

A razor embodying the above features may be made at little expense, the blades are interchangeable and may be readily removed for cleaning without having to separate any parts of the frame.

The relative arrangement of the parts may be changed without departing from the spirit of my invention.

Having described my invention what I claim is:

In a safety razor, the combination of a plurality of frame members hinged to open lon-

itudinally and to hold a blade between them, a handle on one of said frame members a spring adapted to open the other of said frame members and a catch located near the juncture of the frame member and handle and consisting of a reciprocating pin adapted to be moved longitudinally into engagement with the opening frame member and having a projecting finger piece and a spring adapted

to hold said pin in engagement with said opening frame member.

Signed at the city, county and State of New York, this 19th day of September, 1908.

JOSEPH STOLPER.
